UNITED STATES PATENT OFFICE.

ALLEN CURTIS, OF GLENS FALLS, NEW YORK, ASSIGNOR TO INTERNATIONAL PAPER COMPANY, OF NEW YORK, N. Y., A CORPORATION OF NEW YORK.

GRINDER FOR THE PRODUCTION OF WOOD-PULP.

1,164,074.

Specification of Letters Patent. Patented Dec. 14, 1915.

Application filed May 17, 1913. Serial No. 768,198.

To all whom it may concern:

Be it known that I, ALLEN CURTIS, a citizen of the United States, residing at Glens Falls, county of Warren, State of New York, have invented certain new and useful Improvements in Grinders for the Production of Wood-Pulp; and I do hereby declare the following to be a full, clear, and exact description of the invention, such as will enable others skilled in the art to which it app pertains to make and use the same.

My invention relates to certain new and useful improvements in grinders for the production of wood pulp; that is to say, in grinders of that type wherein the wood is forced into contact with the periphery of a grind-stone by means of power pistons operating in pockets wherein the wood is inserted.

20 In wood grinders of this type, it is customary to insert the pieces of wood to be ground into the pockets lengthwise, and to force them toward the periphery of the grind-stone by having the pressure shoe of the piston rod exert its pressure from a point substantially midway of the length of the pocket, a single piston being used for each of the several pockets of the grinder.

According to the present invention, there 30 are substituted for the single piston heretofore employed, two pistons, located at opposite sides of the longitudinal center of the pocket, and each having a separate pressure shoe. By this arrangement, it is feasible to 35 employ grind-stones of greater width to advantage in the grinding of the wood, and nevertheless to attain the necessary pressure of contact required for speedy operation. Consequently, the wood to be ground need 40 not be cut up into the shorter lengths now customary, and a corresponding economy is effected because of the lesser amount of saw- 45 duct wasted in cutting the wood up into lengths. So also, the circumstance that the pistons and their pressure shoes are multiplied for each pocket and are independent of each other permits them individually to adjust themselves to the wood and thereby to produce a more uniform or equalized contact 50 between the wood and the periphery of the grind-stone than is customary in grinders of the ordinary construction.

In the accompanying drawings, Figure 1 represents a longitudinal section of a wood

grinder constructed in accordance with my 55 invention; Fig. 2 represents a cross-sectional view thereof on the line 2—2 of Fig. 1.

Similar letters of reference indicate similar parts in both views.

Referring to the drawings, A indicates 60 the frame or housing in which is mounted the rotatory power shaft B of the grind-stone C, said shaft being journaled in suitable bearings, as shown. Upon the housing A are bolted the several pockets D of the 65 grinder, which pockets may, as is usual, be three in number. The pockets are open at one end for the reception of the wood, and are provided with doors or gates a for closing the open ends when desired. 70

Each pocket is provided with a cap or lid E, preferably cast in a single piece. At opposite ends of this lid are the pressure cylinders F, each containing a piston G and depending pipe b, which latter makes a sliding tight joint with a stuffing box c in the end of its cylinder. As indicated in Fig. 2, the several pistons are adapted to be moved outwardly and inwardly by whatever motive fluid is employed (preferably water under pressure) admitted and exhausted through the ports and passages shown, in a manner well understood by those skilled in the art. 75

Each pocket is provided with guides d 85 for the pressure shoes H, fluted on their lower surfaces and carrying friction rollers e. The shoes H are connected by a rod I, which passes through the tube b, with the piston G, this connection being effected by means of a 90 connecting head f having sufficient freedom of motion to permit small variations in the angular position of the shoe H to accommodate the latter more advantageously to the more or less irregular contour of the wood 95 to be ground.

The admission of the water or other pressure fluid to the rear of the pistons forces the shoes H against the wood and exerts the necessary pressure of the wood against the 100 periphery of the grind-stone essential for the grinding operation, water being supplied to the grind-stone to the amount required, as is customary in the making of wood pulp. The individual shoes of the 105 pistons accommodate themselves separately to the surfaces of the wood, and have the effect of forcing it against the grind-stone.

from two centers of pressure at opposite sides of the longitudinal center of the wood, instead of from one center of application as heretofore. As a consequence, the wood is found to hug the surface of the grind-stone more closely and more uniformly, and the grinding action of the stone is exercised to correspondingly increased advantage in the operation of the machine. So also, if 10 it is found that a greater pressure is required at any particular interval of time, in the one cylinder than in the other, the means are at hand for obtaining that result, by reason of the independent control of each 15 provided in the arrangement shown.

The feature of employing the pipe *b*, instead of the rod *I*, as the sliding element of the stuffing box for the several pressure cylinders, permits the cylinders to be effectively packed against leakage, and takes all 20 lateral strains off the said sliding element, the rod *I* being connected directly to the head of the piston, so as to receive the full effect of the push thereof, while, at the same 25 time, the said rod is adapted to move laterally to the limited extent contemplated, without coming in contact with the walls of the pipe *b*. The full effect of the piston is, therefore, exerted through the shoe, upon 30 the wood, with the avoidance of any possibility of interfering with the free movement of the pipe *b* in the stuffing box and with the avoidance of the wear that would be due to side strains.

I believe it to be wholly new in the art, to so construct the pressure mechanism for forcing the sticks of wood against the periphery of the grind-stone that the sticks are followed up and forced against the 35 stone at each end without regard to the pressure or advance at the opposite end; and it will be manifest to the skilled mechanician that the details of construction herein shown may be modified, provided this 40 mode of action is retained.

Having thus described my invention, what I claim is:—

1. A grinder for the production of wood pulp, comprising a cylindrical grindstone, 50 means for holding the wood to be ground against the periphery of the stone in the direction of its axis, and means constructed and arranged to urge each end of the wood forward against the stone independently of 55 the opposite end.

2. A grinder for the production of wood pulp, comprising a cylindrical rotatory grind-stone and stationary pockets for holding the wood to be ground across the 60 periphery of the stone, in combination with pressure shoes located at opposite sides of the center of the pockets, and means for

forcing said pressure shoes independently against the wood.

3. A grinder for the production of wood 65 pulp, comprising a rotatory grind-stone and a pocket for holding the wood to be ground across the periphery of the stone, and independently-acting pressure devices located at opposite ends of the pocket, to act on op- 70 posite ends of the wood.

4. A grinder for the production of wood pulp, comprising a rotatory grind-stone and pockets to sustain the wood to be ground across the periphery of the stone, in com- 75 bination with pressure shoes located at op- posite sides of the center of the pockets; power pistons and connections between the pressure shoes and power pistons having a limited freedom of movement so that the 80 pressure shoes may act individually to force the wood against the stone.

5. A grinder for the production of wood pulp, comprising a rotatory cylindrical grind-stone and pockets to hold the wood 85 to be ground, the cover plate for each pocket carrying two pressure cylinders located respectively at opposite ends thereof, each of said cylinders having its piston connected to a corresponding pressure shoe 90 within the pocket.

6. A grinder for the production of wood pulp, comprising means for holding the sticks of wood to be ground, a grinding device adapted to operate on said sticks, and 95 a plurality of pressure devices operable to act independently of each other at different points in the length of the individual sticks to force the same against the grinding device. 100

7. A grinder for the production of wood pulp, comprising a frame provided with a pocket to hold the wood to be ground, a grinding-device adapted to operate on the wood held in said pocket, and a plurality of 105 pressure devices operable in said pocket independently of each other simultaneously on different portions of the wood, to force the same against the grinding device.

8. A grinder for the production of wood 110 pulp, comprising a frame provided with a series of pockets to receive the sticks of wood to be ground, a rotary grind-stone adapted to operate on the sticks in said pockets, and two pressure devices in each of 115 said pockets operable independently of each other respectively on opposite ends of the sticks.

In testimony whereof I affix my signature, in presence of two witnesses.

ALLEN CURTIS.
